TILTING LADLE

Louis A. Camerota, Burlington, N. J., assignor to
 Florence Pipe Foundry & Machine Company,
 Florence, N. J., a corporation of New Jersey

Application February 21, 1935, Serial No. 7,563

10 Claims. (Cl. 22—83)

This invention relates to tilting ladles and is particularly applicable to ladles of the type used to charge molds on a centrifugal casting machine.

Where a mold is charged by pouring molten iron 5 therein from a tilting ladle, there is a tendency for slag or other impurities in the metal to rise to the top of the ladle, and in order to prevent such matter from being carried over into the mold, it has been customary to skim the surface of the 10 metal by means of a hoe or the like, and thus to remove the impurities before the ladle is discharged by tilting. Such a method of skimming is both dangerous and disagreeable to the operator who must stand close to the top of the ladle 15 and exercise considerable skill under difficult conditions.

It has been proposed to eliminate such difficulties by using ladles equipped with special instrumentalities for skimming the surface of the 20 metal incident to its discharge, but so far as I am aware, such instrumentalities are generally unsatisfactory because their continuous contact with the molten metal causes their rapid disintegration.

The principal object of the present invention 25 is to provide a skimming device for a ladle which, though comparatively simple and inexpensive, is durable and efficient and avoids the disadvantages characteristic of the devices mentioned above. This end I accomplish by the provision of a device 30 which is normally maintained out of contact with the metal content of the ladle and which is automatically moved to a position at the mouth thereof to skim the surface of the metal as the ladle 35 is tilted to discharge its content.

Other objects of the invention are to provide 40 various means for adjusting the skimming device to suit different conditions, and means for controlling the movement of the skimming blade in relation to the tilting movement of the ladle so as to insure a uniform or even flow of metal from the pouring lip of the ladle.

Preferably also the device of this invention is 45 adapted for periodic cleaning, and this is accomplished by means of a pivotal connection between the skimming device and ladle which permits the skimming blade to be readily swung to a position clear of the top of the ladle where it is accessible for easy cleaning.

Still other objects and advantages characterizing my present invention will become more apparent from the description hereinafter set forth of one example or embodiment thereof, having reference to the accompanying drawings. Of 50 the drawings:

Fig. I represents a side elevation of a pouring assembly, including a pair of ladles equipped with a skimming device of my invention, adapted for use with a centrifugal casting machine.

Fig. II represents a plan view of one of the 5 ladles.

Fig. III represents a cross section of the ladle, taken as indicated by the lines III—III of Fig. II.

Fig. IV represents a side elevation of the ladle 10 and the top portion of its supporting frame, showing the ladle moved to the maximum angle of tilt.

Fig. V represents a cross section of the ladle, showing the skimming device in the position which it occupies when the ladle is moved to its 15 maximum angle of tilt; and,

Fig. VI represents a perspective view of the skimming blade.

With particular reference to Fig. I of the drawings, there is shown an example of a pouring assembly 20 of my invention adapted for use with a centrifugal casting machine of the type represented in U. S. Letters Patent No. 1,944,168, granted to me on January 23, 1934. It comprises generally a ladle carriage 1 having upstanding frame members 2, a pair of tilting ladles 3 disposed side by side and pivotally mounted on the frame members, and a pair of pouring spouts 4 supported on the ladle carriage and adapted to convey the molten metal to the ends of parallel flasks 5. 30 The ladle carriage 1 has wheels 6 engaging a track 7 whereby the carriage is movable in the direction of the axes of the pipe flasks 5. The pouring spouts 4 are removably supported on the ladle carriage 1 by brackets 8, 9. Obviously spouts of 35 different sizes may be substituted for the ones shown to take care of different size pipe flasks.

As shown most clearly in Fig. II, the tilting ladles 3 have trunnions 10 which are accommodated within U-shaped slots 11 at the top of the 40 frame members 2, and it will be observed that the axis of the trunnions 10 is substantially coincident with the forward edge of the pouring lips 12 of the ladles, so that the metal discharged from the ladles flows evenly and without appreciable 45 drop to the pouring spouts 4, and thence to the pipe flasks 5. By means of such an arrangement, the ladles 3 may readily be removed from the carriage for the purpose of repair or replacement. In the illustrated example of the invention a 50 flexible cable 15 is employed for simultaneously tilting the pair of ladles, the cable having a hook shaped end 16 which engages the central portion of a connecting shaft 17 at the rear of the ladles, but it will be understood that any convenient 55

means may be employed for moving a ladle about its pivotal axis.

The novel skimming device of this invention is comprehensively designated at 18, and it comprises a U-shaped arm or strap 19 having its ends pivoted on a shaft 20 and having an intermediate portion bridging the pair of ladles and carrying a skimming blade 21 adjacent to the mouth of each ladle. Each skimming blade 21 may conveniently 5 take the form of a flat plate as represented in Fig. VI, and each blade may be disposed substantially vertically through a slot 22 in a plate 23 carried by the strap 19 and held in position by means of wedges 24 which permit adjustment of 10 the blade relative to the strap.

When the tilting ladles are in their normal upright positions, the skimming device 18 is engaged by an adjustable stop 25 in the form of a slotted bar secured to the frame member 2 by 15 bolts 26. The stop 25 is so adjusted as to maintain the bottom edge of each skimming blade 21 above the topmost level of metal in the ladle, while it rests in normal position, as shown in Fig. III. Adjustment of the stop 25 can readily be 20 effected by loosening the bolts 26, sliding the bar in the direction of its long axis, and subsequently tightening the bolts. On the U-shaped strap 19 there is attached a cam piece 27 which is adapted 25 to engage a cam 28 mounted on the frame member 2 adjacent to the end of a trunnion 10. The engagement between the cam piece 27 and the cam 28 determines the position of the lower edges of the skimming blades 21 with respect to the flowing metal when the ladles discharge their 30 contents.

The cam 28 has arcuate slots 30 therein through which bolts 31 are inserted for adjustably securing the cam to the frame member 2. In an obvious manner the operation of the cam may be 35 varied by changing its adjustment. Behind the cam 28 there is provided a wearing plate 32 which has a guiding extension 33 disposed inwardly of the cam piece 27 and serving to maintain the cam piece against lateral shifting so that its 40 engagement with the cam 28 is insured. The cam 28 and wearing plate 32 are spaced outwardly of the frame member 2 by means of a U-shaped spacer 34. In order to provide a suitable bearing 45 for the ladle trunnions 10, the frame members 2 at the sides of the ladle carriage are preferably 50 reinforced by a block 35, and adjacent to the block the trunnion 10 is provided with a collar 36. The trunnions 10 may be conveniently 55 formed by attaching to the ladle beneath the pouring lip 12 a square shank 37, and turning the shank 37 at its ends to cylindrical shape.

Each cam piece 27 is conveniently formed with an elongated tail member 38 which serves to relieve the wear on the point 39 which engages the 60 cam surface. Desirably also the point 39 is hardened so that undue wear is avoided as the point passes over the relatively abrupt indentation in the contour of the cam surface as indicated at 40. Moreover, the tail member 38 assists 65 in limiting lateral movement of the strap 19. When such movement occurs it engages the wearing plate 32 and prevents the point 39 from moving off the cam surface.

The operation of the skimming device of this 70 invention is as follows:

When the ladles 3 are in their normal upright position, the skimming device 18 assumes the position represented in Figs. I and III, the strap 19 being in engagement with the stop 25 and the 75 lower edge of each skimming blade 21 being

spaced at the desired distance above the pouring lip 12. As the ladles are tilted about the trunnions 10, the weight of the strap 19 is transferred from the stop 25 to the cam 28, the point 39 of the cam piece riding along the curved surface of the cam. With continued rotation of each ladle 3, the point 39 of the cam piece 27 travels over the abrupt indentation 40 in the cam surface, and causes each skimming blade 21 to move downwardly toward the forward edge of the 10 pouring lip 12. Whereas the skimming blades 21 are normally out of contact with the metal content of the ladles, as the metal commences to flow from the ladles 3 to the pouring spouts 4, the skimming blades 21 gradually move into the path 15 of the flow and serve to skim the top surface of the metal. The maximum angle of tilt for the ladles is represented in Figs. IV and V. It will be observed that when the ladles are in the 20 positions there shown, the skimming blades do not obstruct materially the flow of metal but merely function to skim the surface thereof. The various adjustments which are provided for the 25 stop member 25 and the cam 28, as well as the adjustable mounting of the blades 21 on the 25 strap 19, make it possible to regulate the action 30 of the skimming device to conform to the particular conditions which are encountered.

When desired, the skimming device may be 35 swung upwardly and rearwardly about the shaft 30 20 on which it is pivoted to the position represented in dot-and-dash lines in Fig. I, in which position the blades 21 are readily accessible for 30 cleaning. As the blades are moved clear of the top of the ladles, there is no danger of matter 35 knocked off the blades falling into the ladles.

It will be apparent that the device of this invention avoids the difficulties and inconveniences which have heretofore been experienced, where 40 attempts have been made to skim the ladles by a manual operation, and it will also be apparent that the desired movements for the skimming blade are accomplished entirely automatically and are controlled in such manner that the skimming blades are brought into contact with 45 the metal only while it is being discharged from the ladle. This serves to prolong materially the life of the blades.

While I have described my invention with reference to a particular form of ladle carriage, showing 50 an example of the practice of the invention as applied to a double flask casting machine, it will be apparent that numerous changes may be made in the form of the ladle, the skimming device, and the particular means employed for 55 operating the skimming device and of accomplishing the adjustments which have been referred to, all without departing from the spirit of the invention as defined in the annexed claims.

Having thus described my invention, I claim: 60

1. In combination with a tiltable ladle of the character described, a skimming device positioned at the mouth of the ladle and having a cam piece for controlling its movement, and a cam engaging said cam piece and serving to move 65 said skimming device from a position out of contact with the metal content of the ladle to a position where it skims the surface of the metal, said movement of the skimming device taking place as the ladle is tilted from upright to discharging 70 position.

2. In combination with a tiltable ladle of the character described, a skimming device having a blade positioned at the top of the ladle and a cam piece at the side thereof, a frame for supporting 75

the ladle, and a cam adjustably mounted on said frame to engage said cam piece and serving to move said blade from a position out of contact with the metal content of the ladle to a position where it skims the surface of the metal as the ladle is tilted from normal to discharging position.

3. In combination, a support, a ladle tiltably mounted on said support, a skimming device positioned at the mouth of the ladle, and interengaging parts associated with said ladle support and skimming device respectively, said parts cooperating to maintain the skimming device out of contact with the metal content of the ladle 10 while it rests in its normal position on said support and to cause a regulated movement of the skimming device towards the mouth of the ladle to skim the surface of the metal incident to the tilting of the ladle to discharge its content.

20 4. In combination, a support, a ladle tiltably mounted on said support and having a pouring lip substantially coincident with the axis about which the ladle is tilted, a skimming device positioned at the mouth of the ladle adjacent to the pouring lip, and interengaging parts associated with said ladle support and skimming device respectively, said parts cooperating to maintain the skimming device out of contact with the metal content of the ladle while it rests in its 25 normal position on said support and to cause a regulated movement of the skimming device toward the mouth of the ladle to skim the surface of the metal incident to the tilting of the ladle to discharge its content.

30 5. In combination, a support, a ladle tiltably mounted on said support, a skimming device having a removable blade positioned at the mouth of the ladle, and interengaging parts on said ladle support and skimming device respectively, 35 said parts cooperating to maintain said blade out of contact with the metal content of the ladle while it rests in its normal position on said support, and to cause a regulated movement of the blade towards the mouth of the ladle to skim 40 the surface of the metal incident to the tilting of the ladle to discharge its content.

6. In combination, a support, a ladle tiltably mounted on said support, a skimming device pivoted on said ladle and having a blade extending 45 across the mouth of the ladle, adjustable means on said support for determining the position of said blade when the ladle rests in its upright position, and cooperating parts on said ladle support and skimming device respectively and serving to move said blade into contact with the

surface of the metal as an incident to the tilting of the ladle to discharge its content.

7. In combination, a support, a ladle tiltably mounted on said support, a skimming device adapted to extend across the mouth of the ladle 5 and pivotally mounted on said ladle whereby it may be swung to a position to one side of the top thereof, and interengaging parts on said ladle support and skimming device respectively, said parts cooperating to cause a movement of the 10 skimming device towards the mouth of the ladle to skim the surface of the metal as an incident to the tilting of the ladle to discharge its content.

8. In combination, a support, a ladle tiltably mounted on said support, a skimming device 15 having a blade extending across the mouth of the ladle and out of contact with the metal content thereof while the ladle rests in its normal position, said skimming device being pivoted whereby the blade may be swung to a position 20 to one side of the ladle and at a substantial distance therefrom, and interengaging parts mounted on said ladle support and skimming device respectively and cooperating to move said blade into contact with the surface of the metal in- 25 cident to the discharging of the ladle.

9. In combination, a support, a ladle tiltably mounted on said support, a skimming device pivoted on said ladle and having a blade positioned at the mouth of the ladle, an adjustable stop 30 on said support for maintaining said blade out of contact with the metal content of the ladle while it rests in its upright position, and interengaging parts mounted on said ladle support and skimming device respectively and cooperat- 35 ing to move said blade towards the mouth of the ladle to skim the surface of the metal incident to the tilting of the ladle to discharge its content.

10. In combination, a support, a plurality of 40 ladles tiltably mounted on said support, a skimming device bridging the mouths of said ladles and having skimming blades thereon, each positioned adjacent to the pouring lip of a ladle, means for simultaneously tilting said ladles, and 45 interengaging parts associated with said ladle support and skimming device respectively, said parts cooperating to maintain said blades out of contact with the metal content of the ladies while they rest in upright position, and to cause 50 a regulated movement of said blades toward said pouring lips to skim the surface of the metal as the ladies are tilted to discharge their contents.

LOUIS A. CAMEROTA. 55
